(57) **CLAIM**

The ornamental design for a puzzle board, as shown and described.

DESCRIPTION

FIG. 1 is a front perspective view of a puzzle board, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the front of the storage state;

FIG. 10 is a perspective view of the rear of the storage state;

FIG. 11 is an enlarged detail view of area 11 in FIG. 1; and,

FIG. 12 is an enlarged detail view of area 12 in FIG. 2.

The broken lines in the drawings illustrate the portions of the puzzle board, which form no part of the claimed design.

The dash-dot-dash broken lines encircling the enlarged views are for annotative purposes only and form no part of the claim thereof.
